ATTORNEYS.

UNITED STATES PATENT OFFICE.

JULIUS O. VON STETTEN, OF PHILADELPHIA, PENNSYLVANIA, ASSIGNOR TO PHILADELPHIA METAL DRYING FORM COMPANY, OF PHILADELPHIA, PENNSYLVANIA, A CORPORATION OF DELAWARE.

HOSIERY-DRYING FORM.

Application filed July 2, 1927. Serial No. 203,007.

My invention relates to an improvement in hosiery drying forms and more particularly to hosiery drying forms of the type which are adapted to be interiorly heated.

- 5 In the drying of hosiery on hosiery drying forms, and more particularly in the case of full fashioned hosiery, considerable difficulty is met with on account of the seam which extends down the back of the hose.
- 10 In the use of the ordinary hosiery drying form it is necessary to align the seam with an edge of the form, which requires extra care on the part of the operator and wastes time, and the seam acts to space the body of
- 15 the hose adjacent the seam away from the surface of the form, which results in uneven drying, and also to prevent the edge of the form adjacent to which the seam lies from effectively creasing the hose.
- 20 Heretofore it has been suggested to provide a seam receiving groove in hosiery drying forms positioned in or near the edge of the form, however, forms provided with such grooves have not proved entirely satis-
- 25 factory. Such forms having a groove in the edge are ineffective for creasing the hose and those having a groove adjacent to the edge are disadvantageous, since a different set of forms are required to provide rights
- 30 and lefts.

Now it is the object of my invention to provide a hosiery drying form so constructed as to effectively dry and crease seamed hosiery, as full fashioned hosiery, the form 35 according to my invention being so constructed as to accommodate both rights and lefts and to desirably crease the hose with relation to the seam.

Having now indicated, in a general way, 40 the nature and purpose of my invention, I will proceed to a detailed description thereof with reference to the accompanying drawings in which there is illustrated a preferred embodiment and in which:

45 Fig. 1 is a side view of a form embodying my invention.

Fig. 2 is a section on line 2—2, Fig. 1.

Fig. 3 is an enlarged fragmentary view of the subject of Fig. 2.

50 Fig. 4 is an enlarged fragmentary sectional view of a form embodying a modification of my invention.

a indicates a hosiery drying form pro-

vided with a base *b* and made up of side members the edge portions of which are 55 shaped and welded together. The side members are spaced apart between their edges by means of a spacer *c*, which extends from the base *b* to a point near the toe of 60 the form and acts as a partition to divide 65 the form and enable the circulation of steam therethrough.

Between the edges of the side members at the rear of the form is inserted a relatively thin strip *d*, of metal, which is secured in 65 place by welding to the edges of the side member. The strip *d* extends from near the base *b* to the bottom *a'* of the foot and is 70 of a width such that it extends beyond the edges of the side members and into the interior of the form, as shown in Fig. 3.

If desired, a wire *e*, of substantially circular cross section, may be substituted for the strip *d*. The wire *e* is inserted between the edges of the side members to which it 75 is secured by welding. The wire extends from the base *b* to the bottom *a'* of the foot, projects beyond the edges of the side members and has a portion of its surface exposed to the interior of the form. 80

In operation when a stocking is placed on a form embodying my invention, for example, as illustrated in Figs. 1-3, and which is mounted and supplied with steam in the usual manner, the seam may be readily 85 placed to the right or left of the strip *d*, the opposite side surfaces of which form with the opposite side members of the form pockets for the reception of the seam. Thus the stocking may be readily aligned on the 90 form, alignment being effected by merely twisting a stocking on the form laterally until the seam engages one side or the other of the strip *d* throughout its length.

When the seam is engaged with the strip 95 *d*, the outer edge of the strip will act in the drying operation to crease the stocking, and the side surfaces as well as the outer edge of the strip *d* will act to dry that portion of the stocking engaged therewith, since the strip *d* as a whole will be heated by conductivity from that part of the strip within the form and which is exposed to the steam utilized to heat the form as a whole. 100

The operation of a form embodying the 105 modification of my invention illustrated in

Fig. 4 will be similar to the operation above described in connection with the form illustrated in Figs. 1-3.

Having now fully described my invention, what I claim and desire to protect by Letters Patent is—

A hosiery drying form comprising side members, and a relatively narrow strip, a pair of adjacent edges of the side members

being welded together and a pair of adjacent edges of said side members being welded to said narrow strip, said narrow strip extending between said adjacent edges interiorly and exteriorly of said side members.

In testimony of which invention, I have hereunto set my hand, at Philadelphia, Pennsylvania, on this 1st day of July, 1927.

JULIUS O. VON STETTEN.
